UNITED STATES PATENT OFFICE.

CHARLES A. MINARD, OF UNIONTOWN, PENNSYLVANIA, ASSIGNOR OF ONE-HALF TO WALLACK MILLER, OF UNIONTOWN, PENNSYLVANIA.

RAILROAD-TIE.

No. 882,817.

Specification of Letters Patent.

Patented May 22, 1903.

Application filed February 28, 1903. Serial No. 302,868.

To all whom it may concern:

Be it known that I, CHARLES A. MINARD, a citizen of the United States of America, residing at Uniontown, in the county of Fayette and State of Pennsylvania, have invented certain new and useful improvements in Railroad-Ties, of which the following is a specification, reference being had thereto to the accompanying drawings.

This invention relates to certain new and useful improvements in railway-ties; and the invention has for its primary object to provide a strong and durable metallic tie to which rails may be easily and quickly secured.

Another object of this invention is to provide a metallic tie that can be easily handled and readily embedded and tampered in the ballast of a road-bed.

Briefly described, I construct my improved tie of light and durable metal, the tie conforming substantially to an oblong box or vase having open ends and a curved top. The bottom of the tie is cut away centrally thereof to reduce the weight of the same, and the top of the tie adjacent to its ends is cut away to permit of the rails resting upon wooden blocks or plugs inserted in the open ends of the tie.

The detail construction of my improved tie will be hereinfor more fully described and claimed, and, referring to the drawings accompanying this application, like numerals of reference designate corresponding parts throughout the several views, in which—

Fig. 1 is a perspective view of my improved tie; Fig. 2 is a longitudinal sectional view of the same, and Fig. 3 is a perspective view of one of the wooden blocks or plugs used in connection with the metallic tie.

I construct my improved tie substantially the shape of the present type of tie in use, with the exception that in forming my improved metallic tie I provide the same with a curved or arch-shaped top 1. The bottom 2 and the side walls 3 3 of the tie are cut away intermediate of its ends, as at 4 4, to reduce the weight of the tie. The curved or arch-shaped top 1 of the tie is provided with transverse slots 5 5 adjacent its ends, the object of which will presently appear.

In connection with the metallic tie I use wooden blocks or plugs 6 6, said blocks hav-

ing beveled ends 7 7, and the upper faces 8 of said blocks are beveled corresponding to the curved or arch-shaped top 1 of the tie. The blocks 6 6 are made of such a length that they may be inserted in the cut-away portions 4 4 of the tie and then moved outwardly into the ends of the tie to become wedged therein and retained therein by spikes 9 9, employed for holding a rail 10 in engagement with the tie. First one block is inserted in the end of the tie from the central portion thereof and then its associate block, at which time the rails are placed upon the blocks within the recesses 5 5 and spiked thereto by the ordinary form of spike. The spikes in this instance serve the double function of holding the blocks 6 6 within the tie and retaining the rails 10 10 upon the tie.

The blocks 6 6 of the tie are protected from the forces of nature and any injury that they may receive were they not protected by the metallic portion of my improved tie. The construction of the tie permits of the same being embedded in the ballast of a road-bed, and as the ballast entering the central portion of the tie it will be prevented from becoming displaced and will form a strong and durable foundation for the rails over which the rolling-stock passes.

In connection with the tie a plate 11 can be used, said plate being used when the tie rests upon a ballast or road-bed and is not embedded therein.

The tie-rods (not shown) may be used in connection with the wooden blocks of my improved tie to prevent said blocks from splitting; but said tie-rods are not essential, and consequently their use is arbitrary.

By the employment of my improved tie danger of the rails spreading is reduced to a minimum owing to the rails being lodged in the seats 6, the outer side walls of which prevent lateral movement of the rails.

Such changes in the construction of my improved tie as are permissible by the appended claims may be resorted to without departing from the spirit and scope of the invention.

What I claim, and desire to secure by Letters Patent, is—

A railway-tie comprising a hollow metal box, of greatest depth at its center and having the top plate thereof tapering from the

center thereof toward each end of the case, the said top plate having rail-seats adjacent each end thereof, and the side walls and base of the case being cut away, and wooden plugs 5 fitted in the ends of the metal case and having inclined upper faces fitting the inclined underneath face of the top plate.

In testimony whereof I affix my signature in the presence of two witnesses.

CHARLES A. MINERD.
